UNITED STATES PATENT OFFICE.

WILBERT F. BARRETT, OF HAVERHILL, MASSACHUSETTS.

PIN-SETTING MECHANISM.

1,335,638.

Specification of Letters Patent. Patented Mar. 30, 1920.

Application filed July 7, 1919. Serial No. 308,937.

To all whom it may concern:

Be it known that I, WILBERT F. BARRETT, a citizen of the United States, residing at Haverhill, in the county of Essex and State of Massachusetts, have invented a new and useful Pin-Setting Mechanism, of which the following is a specification.

This invention relates to mechanism for setting ten pins, duck pins, candle pins, and the like, one of its objects being to provide simple and efficient means whereby the pins, when moving toward their respective positions in the setting mechanism, will be automatically arranged with their large ends or bases in advance, thereby insuring against assembling the pins with some of them in inverted positions.

Another object is to provide distributing mechanism adapted to be operated by the weight of the pins as they move through the apparatus, whereby the pins will be directed into separate chutes and thence to delivering and elevating means.

A still further object is to provide means under the control of the pins, for unlocking the distributing mechanism, and additional mechanism under control of the pins for reversing the action of the distributing mechanism.

With the foregoing and other objects in view, which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings—

Figure 1 is a view partly in section and partly in elevation, of the setting apparatus, only one of the vertical guide tubes being shown.

Fig. 2 is a plan view of an alley, parts being broken away, and showing the positions of the tubes leading to the "spots," the gutter conveyors, and the receiving hopper.

Fig. 3 is a front elevation of the distributing mechanism.

Fig. 4 is an enlarged transverse section through the distributing mechanism and

showing the locking and reversing mechanism.

Fig. 5 is a detail view of the lock.

Fig. 6 is a view partly in section and 60 partly in elevation of the pin engaging portion of the reversing mechanism.

Referring to the figures by characters of reference, 1 designates an alley having the usual side gutters 2. In the present instance, however, an endless belt 3 is located with its upper run forming the bottom portion of the gutter. The belts are mounted on sheaves 4 secured to transverse shafts 5 under the alley and these shafts are adapted 70 to be driven in any suitable manner, as by a belt 6.

A hopper 7 is provided at the back end of the alley and takes the place of the usual "pit," and extending from the bottom of 75 the hopper is an inclined outlet tube 8 having a delivery arm 9 extending downwardly therefrom, said arm being tubular. A pocket 10 is provided in line with the tube 8 and above the arm 9. The parts are so proportioned that should a pin move endwise through the tube 8 with its base first, it would tilt over the end of the tube 8 and gravitate, base first, into the delivery tube or arm 9. If, however, the pin should slide 85 neck first through the tube 8, the neck portion would pass across the upper end of arm 9 and into the pocket 10 before the base of the pin would come to position above the arm 9. Thus, as soon as the base of the pin 90 comes to position above the arm 9, it will drop down into the arm 9 and the pin will therefore descend base first. The provision of the pocket 10 and the particular arrangement of tube 8 and arm 9 results, therefore, in the 95 automatic adjustment of the pins so that all of them are caused to move base first downwardly through the arm 9.

The arm 9 opens downwardly into a guide tube 11 having a longitudinal slot. An endless belt 12 is supported close to this tube and has fingers 13 outstanding therefrom and spaced apart a distance slightly greater than the length of a pin to be set. One run of the belt is parallel with the slot so that 105 the fingers will move successively into the slot, as shown. Thus as a pin enters the guide tube 11 base first, it will strike the uppermost finger extending into the tube and move it downwardly approximately the 110 length of the pin.

The guide tube 11 opens downwardly into

the upper end of a distributing tube 14 mounted to swing about the axis of a stem 15 extending laterally from the upper end thereof and secured to the distributing tube 5 and concentric with the axis of movement of the tube, is a gear 16 having peripheral teeth 17 and beveled teeth 18. A locking pawl 19 is mounted on the tube 11, this pawl being in the form of a lever one end of 10 which is movable into engagement with the teeth 17 to hold the gear 16 and tube 14 against rotation while the other end projects into the tube 11 to form a stop, as shown at 20. An angular lever 21 is mounted 15 on the tube 11 and passes across the pawl 19 so that when this lever 21 is swung in one direction it will force the stop projection 20 into the tube 11 and disengage the pawl from the teeth 17, and when the said 20 lever is moved in the opposite direction it will actuate the pawl so as to engage the said teeth and withdraw the stop from the tube 11. A rod 22 is slidably mounted on the tube 14 and moves therewith and one 25 end of this rod is connected to the lever 21 close to the axis of movement of the tube 14 while the other end of the rod has an outstanding lug 23.

The belt 12 is mounted on pulleys 24 one 30 of which has a gear 25 revoluble therewith. A frame 26 is slidably mounted below the said gear and has a shaft therein indicated at 27 on which are secured spaced gears 28 either of which is adapted to be engaged 35 by the gear 25. Opposed beveled gears 29 are also carried by said shaft and the beveled gear teeth 17 project therebetween. A rack 30 is carried by the slideable frame and is engaged by a segmental gear 31 pivotally 40 mounted on a suitable support. Oppositely extending arms are extended from this gear 31, as shown at 32 and by rocking the arms and gear, the rack 30 will be actuated so as to move one of the gears 29 into mesh 45 with teeth 17 and one of the gears 28 into mesh with gear 25. Thus motion can be transmitted from the gear 25 to cause the gear 16 to rotate in either direction desired and likewise cause the tube 14 to swing 50 in either of two directions.

The distributing tube is adapted to swing across the open upper ends of a series of downwardly diverging receiving tubes 33 the lower ends of which incline forwardly 55 as at 34 to form delivery mouths 35 in the bottoms thereof and which are adapted to discharge into a box 36. This box can be of any construction desired and can be tilted in any desired manner, as by means of 60 solenoids 37. This part of the mechanism constitutes in itself no part of the present invention and has been shown in detail in my co-pending application #278,112 filed Feb. 20th, 1919.

65 Each of the end tubes of the series indi-

cated at 33 has an enlarged portion 38 and projecting into these portions are gripping fingers 39 slidably mounted and limited in their upward movement by bails 40 pivotally connected to the tubes and by the upper 70 ends of the slots. Springs 41 pull upwardly upon the fingers and extending loosely through openings in the outer ends of the fingers are rods 42 pivotally connected to the ends of the arms 32. Thus when a pin 75 is directed into one of the end tubes 33 by the tube 14 it will come against the end of the finger 39 in said tube and move it downwardly a sufficient distance to allow the pin to pass the end of the finger and fall 80 into the mouth 35. During this downward movement of the finger the walls of the opening therein will grip upon the rod 42 and pull it downwardly against the action of the light spring 41 and, as the pin becomes 85 disengaged from the finger, said finger will be moved upwardly back to its initial position, sliding along the rod 42 during such movement. This initial downward movement of the finger is sufficient to 90 swing the arms 32 and the gear 31 so as to disengage the gears 29 from the teeth 18 and hold the parts in neutral position. The next time a pin is dropped into said end tube the finger will be again lowered and 95 will move the rod 42 downwardly an added distance sufficient to complete the movement of the segment 31 and bring one of the gears 29 into mesh with the teeth 18. The gears are thus arranged to cause the 100 tube 14 to swing away from the end tube 33 when the gear 16 is again actuated.

Every one of the tubes 33 has a lug 43 projecting thereinto from a rod 44 which is slidably mounted on the tube and a head 105 45 is located at the upper end of each rod for engagement with the lug 23 on the rod 22.

After the box 36 has been filled with a set of ten pins it is tilted so as to cause the pins 110 to slide into spouts 46 opening into guide tubes 47 arranged vertically under the alley and extending upwardly to openings 48 in said alley. Plungers 49 are adapted to move within the tubes 47 so as to elevate the pins 115 through the openings, said plungers forming the spots on which the pins are left standing. The means for operating the plungers constitutes no part of this invention and has not been shown or described. 120

Assuming that the tube 14 is located to direct a pin into one of the end tubes 33 after the tenth pin of a set has already been delivered thereto, it will be understood that when the said tenth pin was directed into 125 said tube 33 the gears 29 will be thrown to neutral position. As the pins are hit on the alley and thrown or drawn back into the hopper 7, they gravitate one at a time into the tubes 8, thence into arm 9, and then into 130

the tube 11 where they engage and move the fingers 13. As a pin moves the finger 13 and the belt 12 the gear 16 is operated but as the gears 29 are in neutral positions the segmental gear 31 will not be operated or the position of the tube 14 changed. Consequently the pin, in leaving the tube 11 will press against the beveled end of stop 21 and push said stop outwardly so as to actuate lever 21 and force it into engagement with the teeth 17 and thereby lock the tube 14 against movement. The pin then descends into the end tube 33 and to the box 36, forming the first pin of the next set to be elevated to the alley. In passing through tube 33 the pin shifts the gears, as before explained and also moves against the lug 43 so as to shift rod 44 and pull, through the head 45, upon the lug 23 so as to actuate the rod 22 and disengage the lever 19 from teeth 17. The tube 14 is thus unlocked. The belt 12 being now free to move is actuated by the next pin engaging one of its fingers 13 and as the pin descends the belt operates the gears and causes the tube 14 to swing into register with the second tube 33 of the series. The operation hereinbefore described is then repeated, the lug 23 moving successively into engagement with the heads 45. The tenth pin is finally delivered to the tenth tube of the series and, when so delivered, will move the gears 29 to neutral position so that the tube 14 will remain stationary and deliver the first pin of the next set into the same end tube.

What is claimed is:—

1. In pin setting apparatus the combination with separate pin receiving tubes, a guide tube, means for directing pins from an alley into the guide tube, a movably mounted distributing tube, and means operated by the passage of the pins through the guide tube for shifting the distributing tube successively into communication with the receiving tubes.
2. In pin setting apparatus, the combination with separate pin receiving tubes, a guide tube, a distributing tube movably mounted and communicating with the guide tube, and means operated by pins passing through the guide tube for shifting the distributing tube into communication with the receiving tubes successively, of means operated by the pins when passing into the distributing tube for locking said tube against movement, and means operated by

said pins when leaving the receiving tubes for unlocking the distributing tube.

3. In pin setting apparatus the combination with separate pin receiving tubes, of a 60 guide tube, means for directing pins therefrom to an alley, a distributing tube in constant communication with the guide tube, means operated by a pin within the guide tube for shifting the distributing tube from 65 one to another of the receiving tubes, means operated by said pin when leaving the guide tube for locking the shifting means to hold the distributing tube against movement and to support the next following pin within the 70 guide tube, and means operated by the pin when leaving the receiving tube for unlocking said means.

4. In a pin setting apparatus the combination with separate radially disposed pin receiving tubes, a guide tube and means for directing pins from an alley to the guide tube, of a distributing tube in communication with the guide tube and mounted to move successively into communication with 75 the respective receiving tubes, pin actuated means within the guide tube, gearing operated by said means for shifting the distributing tube, and means operated by the movement of pins successively into and 80 through one of the receiving tubes for successively shifting the gears to bring them to neutral and reverse positions respectively.

5. In pin setting apparatus, the combination with a pin receiving hopper, and an outlet tube extending therefrom, of a tubular arm depending abruptly therefrom, and a pin-neck-receiving pocket in line with the outlet tube and projecting past the outlet arm.

6. The combination with an alley having gutters, a pin receiving hopper, and endless belts within the gutters and leading to the hopper, of an outlet tube extending from the hopper, a pin-neck receiving pocket at 100 the end of the tube, a downwardly extending tubular arm at the inner or open end of the pocket, and pin distributing mechanism supplied by the arm.

In testimony that I claim the foregoing 105 as my own, I have hereto affixed my signature in the presence of two witnesses.

WILBERT F. BARRETT.
